UNITED STATES PATENT OFFICE.

ERASTUS WOODWARD, OF SOMERVILLE, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

LEVELING-MACHINE JACK.

1,076,618.

Specification of Letters Patent.

Patented Oct. 21, 1913.

Application filed July 21, 1906. Serial No. 327,136.

To all whom it may concern:

Be it known that I, ERASTUS WOODWARD, a citizen of the United States, residing at Somerville, in the county of Middlesex, 5 State of Massachusetts, have invented an Improvement in Leveling-Machine Jacks, of which the following description, in connection with the accompanying drawings, is a specification, like letters on the drawings 10 representing like parts.

This invention relates to machines for beating out or leveling the soles of boots or shoes. While the same is particularly useful in that type of beating out or leveling or sole 15 pressing machine wherein very heavy and direct pressure is brought to bear upon the sole of a boot or shoe by molding means shaped to the desired conformation of the sole of the boot or shoe, as for example for a 20 shoe of the McKay type, such shoe being usually interiorly supported upon a metallic jack or last, yet the invention is also applicable for use in that type of machine wherein a welt shoe, interiorly supported 25 upon a wooden last, is subjected to the molding pressure of a moving roller, oscillatory form or the like. In the former type of leveling machine referred to wherein the shoe is subjected to the heavy direct pressure 30 sure of shaped molding means, the supporting jack or last must be of the proper size for each size of shoe the sole of which is to be beaten or leveled and, hence, must be shifted for every change in size of shoe. 35 Furthermore, not only is a metallic last or jack for use in the leveling operation costly in itself, but the provision of a large number of such metallic lasts or jacks to fit the different sizes of shoes is a matter of very large 40 and serious expense.

By my invention I am enabled to substitute for such metallic last one that is much cheaper to produce and that can be much more readily handled. While in the type 45 of my invention herein disclosed I preferably employ a wooden last yet any suitable material may be used. Not only is such a last as I have referred to as embodying one type of my invention intrinsically cheaper 50 than the usually employed metallic last, but the shoe manufacturer may readily and conveniently procure a range of such lasts

of varying sizes and shapes suitable for use with the large variety of shapes and sizes of shoes in the sole leveling or pressing operation, by increasing his order for lasts of various sizes and shapes suitable for use in the lasting operation in adding thereto an order for similar or additional lasts to be used in the sole pressing or leveling operation.

While in that type or embodiment of my invention which I have selected for illustration and description I have shown the last or jack as adapted to be used in connection with a complementally shaped mold whereby the shoe may be subjected to very heavy direct pressure, it will be understood that I am in no sense limited to the use of such type of molding means but that any desired type of molding means may be employed.

In the sole pressing or leveling operation and particularly when a working or locking pressure is employed, a wooden or other non-metallic last toe is liable to be broken under the application of such pressure. While in the present embodiment of my invention I have disclosed a type of exterior toe supporting means whereby many advantages are secured I am not restricted to the use of such mechanism, although the same is peculiarly useful in connection with my improved last, one embodiment of which is herein disclosed.

The above enumerated and other advantages of my invention which flow therefrom will be readily apparent from the ensuing description of one type or embodiment thereof.

Having reference, therefore, to that single type or embodiment of my invention which I have chosen for illustration:—Figure 1 represents a side elevation of the last and the exterior toe support for the shoe together with the means for bringing said parts into effective relation thereto and withdrawing them therefrom, the lower portion of the last support being shown in section; Fig. 2 is a side elevation partly in section of the exterior toe support, the means to lock the same in its effective operative position and the toe support sustaining means, the latter being shown as depressed and the toe support being shown as unlocked. Fig. 3 is a front

2

elevation of the parts shown in Fig. 2 but with the toe support sustaining means elevated and the toe support locked in effective operative position. Fig. 4 is a side elevation, partly in section, of the devices shown in Fig. 2, but representing the toe support sustaining means elevated and the toe support as locked in effective position; Fig. 5 is a front elevation of the crank disk for controlling the movements of the toe support sustaining means. Fig. 6 is a side elevation of the cam having a spiral cam groove for imparting movement to the rear or heel member of the last; Fig. 7 is an end view from the rear of the machine, showing the rear or heel member of the last and the means for operating the same to move it relatively to the body or forward portion of the last; and Fig. 8 is a detail in vertical section showing the friction connections between the rear or heel portion of the last and the projection or roller that is adapted to play in the spiral cam groove of the cam for operating said heel portion, certain of the parts being shown in elevation.

Having now reference to that type or embodiment of my invention which I have chosen to set forth in this application in order to explain the principles thereof and 30 one manner of applying the same in practice;—In the drawings, and referring more particularly to Figs. 1 and 7, the jack support is indicated at 1, the same being ordinarily an in and out moving table, such, for instance, as illustrated in U. S. Patent to Heys, 581,825, May 4, 1897. Or, if desired, it may and preferably will be a table corresponding to that of Patent No. 939,372, November 9, 1909. Mounted to slide longitudinally on the said support is a metallic last base 6 (see Fig. 1). I obtain many of the advantages of a metallic shoe last that is adapted to receive heavy direct pressure from the complementary mold used in beating out or pressing or leveling the sole of a shoe, by providing the said metallic last base with a broad and generous upper end or last support 7, whereon is received a wooden member 8 constituting the last proper and being 45 as shown complementary to the mold member 9 (see Fig. 1) when such type of molding means is employed. The member 8 is sometimes termed a follower, but for identification herein will be known as the last or last member. The said last member proper is 50 preferably formed of wood or of other material that is cheaper or more convenient to provide than that ordinarily used in the production of jacks or lasts for sole pressing or 55 leveling, and the same is preferably of such relatively small extent vertically or in the direction of application of the molding force that the full benefit of the metallic base or support 6 is received during the pressing or 60 beating out or leveling action upon the sole 65

of the boot or shoe. That is to say, the vertical extent of the last 8 is preferably not so great as to neutralize or counteract the rigidity or firmness afforded by the last base 6. In the present type or embodiment of my 70 invention I have shown the line of separation between the last 8 and last base 6 as terminating in the vicinity of the base of the instep of the boot or shoe, and also as terminating in the vicinity of the broadest portion of the last 8, since I find such defined construction to possess many advantages in this type of my invention. It will, however, be understood that I may select such line of support between the last base and last as 80 may secure the advantages of my invention.

I have discovered that if a mold be positioned or aligned with the shoe when supported upon a jack or last, with regard to some critical or predetermined point of the sole thereof, I may employ a single mold or molding means in conjunction with a plurality of different sizes of lasts and, hence, may employ a very limited number of molds or molding devices in conjunction with the 90 entire range of lasts necessary to accommodate the various sizes and shapes of boots and shoes. I may select any suitable portion of a shoe sole or shoe as the critical or predetermined point, but in this embodiment or type of my invention I have chosen for such point the bend or curve of the sole intermediate the forward portion of the shank and the tread. I therefore, in this embodiment of my invention, provide means 95 to secure the last upon the last base in predetermined position with regard to the mold or molding means, so that whatever size of last be employed, the predetermined or critical point thereon may be correctly aligned 100 with the corresponding point of the mold. Thus, I may employ quite a large number of varying shapes and sizes of lasts with a single mold and yet correctly press or level the sole of the shoe positioned thereon and 110 so reduce to a minimum the number of molds necessary for use with the entire range of sizes and shapes of boots and shoes. Various means may be employed to position the last upon the last support in correct and 115 accurate alignment with regard to such critical or predetermined point as has been selected. I have, however, in this embodiment of my invention, shown in dotted lines in Fig. 1 a positioning pin 12, rigidly seated in 120 an upwardly inclined socket in the last base 6 and projecting upwardly from the upper face thereof to receive thereon the last 8 which, for this purpose, is provided with a correspondingly and obliquely disposed 125 socket 13, adapted to tightly fit the pin. The positioning pin 12 is preferably, though not necessarily so located that the corresponding socket in the last extends to the vicinity of the bend or curve between the 130

forward portion of a shank and the tread. By thus locating said pin the last may be most conveniently applied to its support and most securely positioned thereon inasmuch as the pin passes through that portion of the last having the greatest vertical extent. I may substitute for the said pin any suitable device to position and lock the lasts upon the last base but I prefer in this embodiment of my invention to employ the pin 12 as a positioning means and preferably locate the same at the forward portion of the last and employ a separate locking means. Inasmuch as with the use of certain types of molding means, when pressure is thereby brought upon one portion of the sole, there is a tendency to tip or tilt the sole and last upon its support in the direction of the application of the molding force, I preferably provide a locking means to operate in conjunction with the opposite portion of the last and shoe to prevent such tipping or tilting, and further to accurately position and maintain the last upon its support. In this type or embodiment of my invention I have chosen to employ as the locking means a second pin 14 extending from the upper face of the last base 6 and preferably at an angle to that of the first or positioning pin 12. In order to position the last 8 upon the said pins, the pin 14 is slidingly mounted in an upwardly inclined socket 15 in the upper portion of the last base 6, the lower portion of said socket being of reduced diameter, as shown at 15', and extending to the adjacent surface of the last base 6. Within the said socket 15 is slidingly disposed a locking or positioning pin having a head 14 adapted to engage a corresponding socket 14' in the last 8 and having depending therefrom a reduced portion or spindle 17, extending to the outer adjacent surface of the last base 6 and preferably having at its end a knob or enlargement 18 that may be grasped by the operative to withdraw the pin head 14 from engagement with the socket 14' in the last. Between the lower end of the head of the said pin and the base of the enlarged portion of the socket 15 is preferably provided a coiled spring 19 tending normally to project the head 14 of the pin into the socket 14' of the last 8, thereby to position securely the same upon the last base 6. When it is desired to apply a last to or to remove one from the last base 6, the knob 18 is grasped by the operative and the head 14 of the pin is withdrawn from the socket 14' of the last 8, whereupon the last may be lifted or withdrawn from its engagement with the positioning pin 12.

It is, of course, obvious that within certain rather well defined limits I may employ a single last 8 for shoes differing somewhat therefrom both as to size and shape inasmuch as even with such a shoe I may

by my invention aline the same in a predetermined position with respect to the molding means.

I preferably form the last or interior shoe support as an expansible one to fit different sizes or shapes of boots and shoes and in this type of my invention I preferably accomplish this result by providing the last with a separable member here shown as a rear or heel member 9' of any suitable shape and material, the same being adapted to be moved relatively to the body portion of the last so that the said heel member may be positioned in close or effective relation with the heel portion or rear of the boot or shoe, regardless of the size of the latter. Any suitable means may be employed to impart relative movement to the said heel member and forward member of the last and either member may be the movable one. I prefer, however, to impart movement to the heel member and as one suitable means therefor have pivoted the lower extended end of said heel member (see Figs. 1 and 7) upon a shaft 5 supported in depending frame brackets 3. I preferably also provide means tending to press or hold the heel member of the last rearwardly or into effective binding relation with the shoe and to that end have provided (see Fig. 7) preferably upon the lower portion of the said heel member a lug 21, against which impinges a spring pressed pin 22 mounted in a socket in the adjacent portion of the jack or last support.

As one type of means to impart the described movement to the heel member 9' of the last and preferably also to impart other movements to be hereinafter described, there is mounted, preferably in the lower portion of the last base 6 (Fig. 1) and in a journal 24 rising from an end thereof, a horizontally disposed shaft 23. Motion may be imparted to the said shaft in any suitable manner, either manually or mechanically, but I prefer to impart motion thereto manually and to that end have provided upon the rear end thereof a crank handle 24'. Preferably between the journal 24 and the adjacent base portion of the last there is fast upon the shaft 23 a preferably cylindrical cam 25, having therein (see Fig. 6 also) a spiral cam groove 26, within which is received for movement therein (Fig. 8) a pin 27 provided upon its cam groove engaging end with the sleeve 27'. The said pin is mounted in an arc shaped horizontally disposed slot 28 in the heel member 9' of the last. The said pin 27 is preferably provided with friction means (Fig. 8) consisting of a concaved spring washer 29 positioned between the washer 30 and the nut 31, whereby the said washer 30 frictionally engages the face of the heel member 9', so that in the described rotation of the cam 25 to 130

bring the heel member 9' into effective engagement with the heel portion of a boot or shoe, the said pin 27 when moved longitudinally by the spiral cam groove 26 of the cam 25 carries therewith the said heel member 9'. When the heel portion 9' has been brought into effective relation with the heel member of the shoe, if further movement be imparted to the shaft 23 in the same direction the pin 27 is permitted to slide in

the slot 28, overcoming the friction of the washer 30 against the said heel member 9', but without losing the degree of expansion already obtained.

15 The described interior shoe support and any suitable means for operating the same may be used with any desired type of molding means, and with or without an exterior toe support for the shoe, but owing to the

20 fact that in the sole leveling or pressing operation the pressure that is brought to bear upon the forward portion of the foot is apt to break down the last, if not of metal, many advantages accrue from the use of an

25 exterior toe support. Therefore in this type of my invention I have disclosed an exterior toe support and have here shown and preferably employ one the toe contacting portion of which is adapted to automatically adjust itself to conform to the contour

30 of the exterior portion of the toe so as to present either a continuous support or what in many instances is the equivalent, a two-point support. If preferred, however, a toe

35 support that does not automatically or even mechanically conform to the contour of the toe of the shoe may be employed. I have here shown, a toe support 32^a to engage the exterior of the boot or shoe, the sole of

40 which is to be beaten out or pressed or leveled, the said support having in this instance (Figs. 1, 2, 3 and 4) a pad 33 of any suitable material, the same being suitably secured as by a dovetailed joint 34 upon the base member 35 provided (Figs.

45 1 and 3) with a set screw 36, adapted to pass upwardly and obliquely through the said base member 35 and into effective relation with the pad 33. In this type or embeddi-

50 ment of my invention I preferably, as previously stated, employ a toe support that automatically conforms substantially to the contour of the toe of the shoe and I may and preferably do secure such automatic conformation by so mounting the toe support that the same may rock as it is brought into engagement with the toe of the shoe to thereby adjust itself and provide either a continuous or a two-point support.

60 Not only is the toe support 32^a shown in this type of my invention as so mounted that it may rock to adapt the face of the pad 33 thereof to the shape of the toe of the boot or shoe, but the said toe support is prefer-

65 ably and is herein shown as provided with

sustaining means whereby it may be moved relative to, or withdrawn from effective supporting relation, so that the shoe and the last may be removed from the last base 6 and another shoe and last substituted therefor or another shoe be placed upon the last. While I hereinafter define the toe support 32^a as preferably having means whereby the same may be depressed from or withdrawn from engagement with the shoe, I use such terms in a broad sense and cover thereby any means for relatively moving the said toe support 32^a with respect to the shoe, inasmuch as it is obviously within the scope of my invention to move the last or interior support of the shoe away from the said exterior toe support, or movement may be imparted in different directions or differential movement in the same direction to both the last or interior shoe support and the exterior toe support, to separate the shoe and the said toe support. I have, however, chosen in this embodiment of my invention to withdraw the toe support from the shoe and preferably do so by depressing the same from contact therewith, although it is obvious that the said toe support may be withdrawn from the shoe in many different ways and in many different directions. Such described movement may be imparted either manually or automatically but in the present embodiment of my invention I have chosen to impart the desired movement manually and preferably employ the manual means provided to impart relative movement to the heel piece and the body or base portion of the last.

To permit the previously described rocking movement of the toe support when such is employed I preferably (Fig. 3) provide the base member 35 thereof upon its under side with a hub 37, and loosely journal the same upon a short horizontal shaft 38, that is mounted (Fig. 1) in vertically elongated bearings 39 in the upper ends of the upright arms 39' of an upright and vertically sliding sustaining member 40 (Fig. 3). The said shaft 38 is preferably mounted near its upper ends with depending pins 41 (Figs. 1 and 3) the lower ends whereof extend into vertical sockets 42 provided in the upper ends of the said upright arms 39' of the sliding sustaining member 40, wherein are preferably contained coiled springs 43, tending normally to force the pins 41 and the shaft 38 upwardly in the elongated bearings 39 in the upright arms of the sliding sustaining member 40. Preferably depending centrally from the hub 37 of the base member 35 of the toe support 32^a (Fig. 3) there is provided an arm 44, the lower end of which is preferably provided with a suitable locking surface such as the here shown are shaped serrated surface 45 (Figs. 1, 2 and 4). Centrally of the sliding sustaining

member 40 and directly beneath the depending arm 44 there is provided a block 46, set in the edge of the said sliding sustaining member, the upper surface of said block being preferably serrated or otherwise conforming to the surface 45 of the lower end of the arm 44.

As has been previously stated, the toe support 32^a is in this type of my invention preferably withdrawn from effective engagement with the toe of the shoe that the same may be withdrawn from the last or the shoe and last, if desired, removed from the last base, after the sole leveling operation upon that shoe has been completed. In returning the said toe support into effective engagement with the toe of the succeeding shoe in the manner to be hereinafter fully described, before the fully effective sustaining position thereof has been reached, the toe support 32^a is permitted to automatically accommodate itself and in this type of my invention to rock upon the shaft 38 so that the pad 33 thereof when the same is employed, as it first lightly engages the shoe may conform in position to the contour of the toe thereof and provide either a continuous or a two-point bearing therefor as has been previously described. In so conforming itself to the contour of the shoe toe the depending arm 44 thereof is oscillated to and fro and is finally brought to rest at a position dependent upon the final and conforming position of the pad 33. This having occurred, the locking or serrated surfaces 45 and 46 are in a manner to be hereinafter fully described brought into engaging or locking relation, so that the toe support 32^a is locked in its position of conformity to the shape of the shoe toe, and the same is preferably rigidly supported as will be further described.

In order, as is preferably done in this type of my invention, to withdraw the toe support 32^a from engagement with the shoe upon the last 8 after the shoe sole has been leveled as by depressing the said toe support, the sliding sustaining member 40 therefor is provided (Fig. 3) with inclined vertical side edges 47-47 that are received in corresponding guide ways 48 in a frame or support 49, suitably secured upon an upright 49', suitably secured upon the lower portion of the metallic last base, between which and the said frame member 49 the sustaining member 40 is mounted for vertically sliding movement.

Near the upper edge of the frame member 49 are mounted pins 50, to which are secured the upper ends of vertically arranged coiled springs 51, the lower ends whereof are secured (Fig. 3) to pins 52 extending from the lower portion of the sliding sustaining member 40, the tendency 65 of the said springs being to maintain the

sustaining member 40 in an elevated position with the toe support member 32^a in effective supporting engagement with the toe of the shoe, the sustaining member being locked in such elevated position (see Fig. 4) by suitably mounted spring pressed pawls 59 and 62 engaging the toothed surface 61 upon the lower portion of the said sustaining member.

While I have specifically described one form of locking means to hold the sustaining member 40 in elevated position it will be apparent that any suitable locking or other means may be employed for the purpose. In order to depress the said sliding sustaining member 40, after the same has been unlocked, any convenient means may be employed. As merely one type of means for accomplishing the desired result, there is mounted upon the shaft 23 (Figs. 1 and 4) a crank disk 53 (Fig. 5), a crank pin 54 projecting from one face thereof being adapted in the partial rotation of the said disk to engage (Fig. 4) a ledge 55 formed upon the rear face of the lower portion of the sliding sustaining member 40 and to depress the said member. The same face of the crank disk 53 is provided at a suitable portion thereof and preferably near its margin (Fig. 5) with a socket 56, adapted to receive therein an end of a horizontally disposed sliding pin 57, mounted in an upright 49' and passing through a vertically disposed slot 57' (Fig. 3) in the lower portion of the sliding sustaining member. The opposite end of said pin is preferably suitably shaped to engage (Fig. 3) a projection 58 from the pivoted pawl 59 adapted to be spring pressed as by a spring 60 into engagement with the said toothed surface 61 upon the sustaining member. There is preferably provided (Fig. 1) a second pawl 62, of shorter length than the first so that one or the other of said pawls may be brought accurately into effective relation with the toothed surface 61 upon the sliding sustaining member 40 when the toe support 32^a has been brought into effective supporting relation to the shoe. The second pawl 62 is preferably provided (Fig. 1) with an arc shaped slot 63, adapted to receive a pin 64 projecting from the face of the pawl 59, so that when the pawl 59 has been withdrawn from engagement with the toothed surface 61, the second pawl is likewise withdrawn therefrom.

At the commencement of the described movement of partial rotation of the crank disk 53 upon the shaft 23 the sliding pin 57 is forced from the socket 56 in the face of the disk into engagement with the projection 58 of the pawl 59 to withdraw both pawls from engagement with the toothed surface 61. In the further movement of partial rotation of the crank disk 53 the

pin 54 thereon engages the ledge 55 of the sliding sustaining member 40 and depresses the same thereby distending the springs 51 and withdrawing the toe member 32^a from effective supporting engagement with the toe of the shoe. In such downward movement of the sliding sustaining member 40 the springs 43 that support the horizontal shaft 38, whereon the toe support is mounted, hold said toe support elevated until the shaft 38 is engaged by the upper ends of the said elongated slots 39 in the upper ends of the upright arms 39' of the sliding sustaining member 40, whereupon the toe supporting member 32^a partakes of the continued downward movement of the sliding sustaining member 40. A shoe the sole whereof has been leveled or pressed, having been removed from the last and another substituted therefor or the shoe and last having been removed from the last support, and another placed thereon, the operative imparts a reverse rotative movement to the shaft 23 by means of the crank handle 24', thereby moving the pin 54 of the crank disk 53 in the opposite direction or upward, the tension of the springs 51 tending to move upward correspondingly the sliding sustaining member 40. During such upward movement of the sliding sustaining member 40 the tension of the springs 43 by which the shaft 38 of the toe support 32^a is upheld, tends to hold said shaft 38 at the upper extremity of the elongated bearings 39 in the arms of the sustaining member 40 so that the locking or serrated surface 45 of the depending arm 44 is out of engagement with the corresponding surface of the block 46. Therefore, in the use of this type of my invention, when the pad 33 of the toe support 32^a first touches the toe of the shoe it instantly conforms itself to the contour of the shoe in the manner previously described. The then continued upward movement of the sliding sustaining member 40 compresses the springs 43 that support the shaft 38 so that the said shaft is seated in the lower ends of the elongated bearings 39 and the locking or serrated surfaces 45 and 46 are at the same time brought into locking relation whereby a rigid support is presented to the toe of the shoe, the sole of which is next to be leveled by the action of the molding means thereon.

During the described reverse movement of partial rotation of the shaft 23 to elevate the sustaining member 40 and the toe support 32^a, the cam 25 acts in the manner previously described to move the heel member 9' of the last into effective engagement with the rear or heel portion of the shoe.

Having thus set forth one embodiment or type of my invention, I wish it to be understood that although the same has been specifi-

cally described yet the terms employed are used in a broad or general sense and not in their specific nature and that the scope of the invention is set forth and defined in the following claims:—

1. In a device of the character described, the combination of a laying or leveling form, a last base having a last supporting surface for engaging and supporting singly a plurality of lasts of different sizes, and last positioning and securing means arranged and extending between the last supporting surface of the base and the last placed thereon to position each last, regardless of its size, with its ball line in an invariable position with reference to the last base that the ball line of lasts of different sizes may register with the ball line of one and the same form when lasts are secured to the base. 70

2. In a device of the character described, the combination of a laying or leveling form, a last base adapted to support singly a plurality of lasts of different sizes, and last positioning means between the last base and a last placed thereon extending in a direction to intersect the ball line of the last when the last, regardless of its size, is connected to the last base by said means, that the ball line of lasts of different sizes may assume the same invariable position to register with the ball line of one and the same form when lasts of different sizes are singly secured to the base. 90

3. In a device of the character described, the combination of a laying or leveling form, a last base adapted to support singly a plurality of lasts of varying sizes with the ball line of said lasts, regardless of size, in the same position, said last base and each of said lasts being provided with complementary engaging means fixed with relation to the ball line of the lasts regardless of variations in size of the lasts that the ball line of said lasts may assume registering position with the ball line of an opposed form when any 110 of said lasts are secured to the last base by said complementary engaging means. 100

4. In a device of the character described, the combination of a last base adapted to support singly a plurality of lasts of different sizes with the ball line of said lasts in the same position, a positioning pin extending from one of said parts, in a direction to intersect the ball line of the last, regardless of its size, the other of said parts having a recess to be engaged thereby, that the ball line of a series of lasts of different sizes may assume an invariable position when the last is placed upon the last base. 115

5. A work support comprising a last base adapted to support singly a plurality of lasts of varying sizes, pins extending between said last base and last positioned thereon to maintain said parts in working relation, and one of said pins having its di- 125

rection such as to intersect the ball line of lasts of different sizes placed upon the last base.

6. A work support comprising a last base 5 provided with an upwardly extending positioning pin, said last base adapted to support singly a plurality of lasts of varying sizes each having a pin receiving socket, said positioning pin and socket being disposed and

10 arranged in the same relation to the ball line of said different sizes to position each last upon the base with the ball line in invariable position regardless of the size of the last, and a locking pin further connecting the base and last.

7. In a device of the character described, the combination of a laying or leveling form, a last base having a last supporting surface for engaging and supporting singly a plurality of lasts of different sizes, last positioning and securing means constructed and arranged between the last supporting surface of the base and the last placed thereon to position each last, regardless of its size, 25 with its ball line in an invariable position with reference to the last base that the ball line of lasts of different sizes may register with the ball line of one and the same form, a heel member, and means to separate the last and heel member while maintaining the last in the invariable position stated.

8. In a device of the character described, the combination of a laying or leveling form, a last base adapted to support singly a plurality of lasts of different sizes, last positioning means between the last base and a last placed thereon extending in a direction to intersect the ball line of the last when the last, regardless of its size, is connected 40 to the last base by said means that the ball line of lasts of different sizes may assume the same invariable position to register with the ball line of one and the same form, a movable heel member, and means for separating it from the last while maintaining said last, regardless of its size, with the ball line in the position stated.

9. In a device of the character described, the combination of a last base adapted to 50 support singly a plurality of lasts of different sizes, last positioning means between the last base and the last to position lasts of different sizes upon the last base as the parts are put together with an initial part of each 55 last intermedial its ends in an invariable position regardless of the size of the last, a prolongation of said positioning means intersecting said initial point of the last, a heel member, and means for separating the 60 last and heel member while maintaining the initial point of the lasts in said invariable position.

10. A shoe support comprising a last base, a last supported thereon, a relatively movable supporting member located with respect

to the last and last base to adapt the shoe support to shoes of different sizes, means for moving said member with relation to the last, and connections between said means and member permitting the continued operation of said means without causing movement of said member after the latter has been moved to the limit determined by the shoe.

11. In a device of the character described, the combination of a last base, a last supported thereon, an interior shoe supporting member, said last and member being relatively movable interiorly of a shoe supported thereby, an actuator for causing such relative movement, and yielding means between the actuator and said member permitting the actuator to continue its movement after relative movement of the last and said member has ceased.

12. A shoe support comprising a last base provided with an upwardly projecting pin and adapted to support singly a plurality of lasts of varying sizes or shapes, with an initial part of the last intermediate the ends 90 of the sole of the last in invariable position regardless of the size and shape of the last, each of said lasts having a socket, a prolongation of which intersects the said initial point of the last, and adapted to be engaged by said pin.

13. A shoe support having a last base adapted to support singly a plurality of lasts of varying sizes, in position defined by a predetermined point on the sole of the last 100 intermediate the ends thereof, positioning means connecting the last base and each last to position the last upon the base with said predetermined point in invariable location regardless of the size of the last, said means comprising divergent pins disposed between the last base and last, one of said pins being arranged on a line intersecting said predetermined point on said last.

14. In a device of the character described, the combination of a last base adapted to support singly a plurality of lasts of different sizes, last positioning means between the last base and last to position lasts of different sizes upon the last base with a 115 predetermined point of each last intermediate its ends in an invariable position regardless of the size of the last, a prolongation of said positioning means intersecting the predetermined point of any last placed 120 upon the base, and an exterior toe support for the toe of the selected last.

15. In a device of the character described, the combination of a last base adapted to support singly a plurality of lasts of different sizes, last positioning means between the last base and last to position lasts of different sizes upon the last base with a predetermined point of each last intermediate its ends in an invariable position regardless of 130

the size of the last, a prolongation of said positioning means intersecting the predetermined point of any last placed upon the base, and an exterior toe support automatically conformable to the toe of the selected last.

16. In a device of the character described, the combination of a last base adapted to support singly a plurality of lasts of different sizes, last positioning means between the last base and last to position lasts of different sizes upon the last base with a predetermined point of each last intermediate its ends in an invariable position, regardless of the size of the last, a prolongation of said positioning means intersecting the predetermined point of any last placed upon the base, an adjustable interior shoe supporting member, and an exterior toe support.
17. In a device of the character described, the combination of a last base adapted to support singly a plurality of lasts of different sizes, last positioning means between the last base and last to position lasts of different sizes upon the last base with a predetermined point of each last intermediate its ends in an invariable position regardless of the size of the last, a prolongation of said positioning means intersecting the predetermined point of any last placed upon the base, an adjustable interior shoe supporting member, an exterior toe support, and means for adjusting the interior shoe supporting member and by its movement permitting the toe support to automatically move to supporting position.

18. In a shoe support, a pivotally mounted toe rest, a lock for restraining movement of the toe rest on its pivot, means acting normally to free the toe rest to such pivotal movement, and means to raise said toe rest into contact with the work while free to swing on its pivot and thereafter cause it to be locked.
19. In a shoe support, a pivotally mounted spring supported toe rest normally free to swing on its pivot, a lock for restraining pivotal movement of said toe rest when the latter is under pressure, sustaining means for said toe rest, and means for locking the sustaining means in position with the toe rest in contact with the work.

20. In a work support, a toe rest, sustaining means therefor normally tending to raise the toe rest into contact with the work, a lock to hold the sustaining means in raised position, and means to disengage the lock to permit lowering of the toe rest.

21. In a work support, a toe rest, sustaining means therefor normally tending to raise the toe rest into contact with the work, a lock to hold the sustaining means in raised position, and means to disengage the lock and means to lower the toe rest.

22. In a work support, an interior expand-

sible shoe support, an exterior toe support, sustaining means for the latter, a shaft, connections between said shaft and the interior expandible shoe support, and between said shaft and the said sustaining means to control the expandible shoe support and the said sustaining means by movement of said shaft.

23. A shoe support, an exterior toe support, means acting normally to move the exterior toe support into toe supporting position, withdrawing means to remove the same from effective supporting relation to the shoe against the stress of the said normally acting means, locking means to hold the said exterior toe support in supporting relation thereto, and means for controlling said locking means.

24. A shoe support, an exterior toe support movable toward and from effective supporting relation to the shoe, means normally acting to move the toe support into toe supporting position, locking means to hold said toe support in supporting relation, and means operative only for causing movement of said toe support from supporting position and for controlling said locking means.

25. A shoe support, an exterior toe support, and sustaining means wherein the latter is yieldingly mounted, said means acting normally to raise the toe support, a lock for holding the said means in raised position, and means for controlling said lock.

26. In a device of the character described, the combination of a shoe support, an exterior toe supporting means, a toe support yieldingly mounted on said means to conform to the toe of a shoe, a lock for holding the toe support in its position of conformation to the toe of a shoe, a lock for holding the toe supporting means in supporting position, and means to trip the last-named lock and depress the supporting means.

27. In a device of the character described, the combination of an interior expandible shoe support, an exterior toe support, sustaining means for the latter, and a common movement imparting means to control the said interior expandible shoe support, and the said sustaining means.

28. In a work support, an interior expandible shoe support, an exterior toe support movable into and out of operative position, means for locking said toe support in operative position, and a common movement imparting means for causing said shoe support to be expanded, for causing said toe support to be moved into operative position, and for rendering said locking means operative.

29. In a device of the character described, the combination of an interior expandible shoe support, an exterior toe support, means for locking the toe support against movement, and means to unlock the toe support.

and contract the same to separate said supports and contract the interior shoe support.

30. In a device of the character described, the combination of an interior expandible shoe support, an exterior toe support, means for locking said supports against relative movement, and means to unlock said supports and simultaneously move one of them positively to separate said supports and contract the interior shoe support.

31. In a device of the character described, an interior shoe support, a pivotally mounted exterior toe support, movable sustaining means therefor, means for locking the toe support against pivotal movement and locking means for said movable sustaining means.

32. A work support comprising an interior shoe support, an adjustable exterior toe support, movable sustaining means therefor, and successively acting locking means, one to hold the toe support and the other to hold the movable sustaining means in operative position.

33. In a work support, the combination of a last base, an interior expandible shoe support, an exterior toe support, means acting normally to move the toe support into the toe supporting position, a lock for holding the toe support in toe supporting position, and a single means for expanding the interior shoe support and freeing the toe sup-

port to movement induced by said normally acting means.

34. In a work support, the combination of a last base, an interior expandible shoe support associated with said base, a toe support, means for placing the toe support in toe supporting position, and a shaft 23 operatively related to said toe support and interior expandible shoe support to simultaneously effect operation of both.

35. In a work support, a last base, a pin 12 extending therefrom in a direction to intersect the ball line of a last placed upon said support regardless of the size of said last, and a pin 14 to lock the last in position on said last base.

36. In a work support, an interior shoe support, an exterior toe support movable toward the toe of a shoe, a movable sustaining means also movable toward and from the toe of a shoe on the interior shoe support, and successively acting automatic locking means one to hold the toe support raised and the other to hold the movable sustaining means in position on said toe support.

In testimony whereof, I have signed my name to this specification, in the presence of two subscribing witnesses.

ERASTUS WOODWARD.
